(57) **CLAIM**

The ornamental design for an ultimate propeller guard, as shown and described.

DESCRIPTION

FIG. 1 is an aft elevation view of the ultimate propeller guard, showing my new design;

FIG. 2 is a fore elevation view of the ultimate propeller guard;

FIG. 3 is a left side elevation view of the ultimate propeller guard;

FIG. 4 is a right side elevation view of the ultimate propeller guard;

FIG. 5 an enlarged top elevation view of the ultimate propeller guard;

FIG. 6 is an enlarged bottom elevation view of the ultimate propeller guard; and,

FIG. 7 is a perspective view of the ultimate propeller guard of my new design.
